CLAIM

The ornamental design for a fishing rod carousel, as shown and described.

DESCRIPTION

FIG. 1 is a left hand perspective view of a fishing rod carousel with the door open, showing my new design; FIG. 2 is a right hand perspective view thereof with the door closed;

FIG. 3 is a front elevational view of FIG. 1;

FIG. 4 is a top plan view of FIG. 1;

FIG. 5 is a bottom view of FIG. 1;

FIG. 6 is a right side elevational view of FIG. 2;

FIG. 7 is a left side elevational view of FIG. 2; and, FIG. 8 is a rear view of FIG. 2.

The broken line showing of the shelves in FIGS. 1 and 3, and the indicia in FIG. 2 and the fishing rod in FIG. 3 is for illustrative purposes only and forms no part of the claimed design.

FIG. 1

FIG. 2

FIG. 3

FIG. 4

FIG. 5

FIG. 6

FIG. 7

FIG. 8
